UNITED STATES PATENT OFFICE.

RALPH L. QUASS, OF HAWTHORNE, NEW JERSEY, ASSIGNOR TO WESTERN ELECTRIC COMPANY, INCORPORATED, OF NEW YORK, N. Y., A CORPORATION OF NEW YORK.

CALL-DISTRIBUTING SYSTEM.

1,308,554.

Specification of Letters Patent.

Patented July 1, 1919.

Application filed October 8, 1917. Serial No. 195,354.

To all whom it may concern:

Be it known that I, RALPH L. QUASS, a citizen of the United States, residing at Hawthorne, in the county of Passaic and 5 State of New Jersey, have invented certain new and useful Improvements in Call-Distributing Systems, of which the following is a full, clear, concise, and exact description.

This invention relates to telephone call distributing systems of the type in which the calls originated by the lines of the exchange are automatically distributed to operators' positions at which connection with the called subscribers' lines is completed. The invention 10 has primarily to do with the provision of means for safeguarding such a system against failures of operation which might result from careless manipulation of the apparatus on the part of the operators, or which 15 might arise from the improper operation of the apparatus itself; the object being to improve and render more efficient and reliable the operation of the system.

Generally stated, the system of the preferred embodiment of the invention herein disclosed provides a plurality of operators' positions each equipped with a number of plug-terminated connecting circuits for completing connection with called subscribers' 20 lines. The connection between these connecting circuits and the calling subscribers' lines is effected through the medium of a number of finder circuits, each of which has an automatic switch at one end for finding 25 and connecting with any subscriber's line that may be calling, and an automatic switch at the other end for selecting an available operator's position and then connecting with an idle connecting circuit at that position. 30 The connecting circuit to which the connection is extended terminates in a plug, and the operator completes connection with the called subscriber's line by inserting the plug into the spring-jack of that line.

45 In the selection of an operator's position by the finder circuit certain devices are operated that render the position inaccessible to other incoming calls, and the position remains inaccessible until certain other apparatus operates to restore its accessibility. Similarly, 50 the selection of an idle connecting circuit by the incoming call renders that connecting circuit inaccessible to other calls until the accessibility of the circuit is restored by taking down the connection.

The idle or accessible condition of a connecting circuit, in the present system, is indicated by the connection of relatively high potential battery with the test conductor associated with the connecting circuit. One 60 of the objects of the present invention is so to organize the system that when, by the accidental grounding of one of the test conductors or otherwise, an abnormal electrical condition of the testing circuits of an operator's position is created, that position is automatically made inaccessible to incoming calls, while at the same time the ability of the operator to supervise existing connections is not interfered with. Another object of the invention is to provide means for 65 signaling the operator of the selection of her position the instant the selection occurs, and for withdrawing the signal after a predetermined time interval, or at the instant the 70 connecting circuit is seized if the seizure takes place before the expiration of that time interval. Another object of the invention is to provide means for preventing holding the operator's position unselectable for 75 more than a predetermined interval in the event of an abnormal operation of the apparatus which controls the connection of the operator's telephone with a connecting circuit when the operator listens in on that 80 circuit. Another object of the invention is to prevent an unintended release of the calling line from the connecting circuit to which it has been extended in case the operator 85 happens to insert the calling plug into the 90 spring-jack of the called subscriber's line in such a way as momentarily to break the connection as the plug moves into the spring-jack. Another object of the invention is to give an operator a characteristic signal or 95 indication when she inserts into the spring-jack of a line the calling plug of a connecting circuit to which a calling line has not been extended.

The preferred embodiment of the system 100 of the invention, in which the foregoing and other objects are attained, is illustrated in the accompanying drawings, in which Figure 1 shows two groups of lines with two line finder switches for making connection 105 therewith, together with the associated circuits and apparatus through the medium of which the lines control the switches; Fig. 2 shows one finder circuit complete, and enough of two other finder circuits to illus- 110

trate the relationship between them; Fig. 3 shows two cord selector switches of one frame with their associated selection controlling apparatus and circuits, together with 5 similar apparatus and circuits for the cord selector switches (not shown) of another frame; and Figs. 4 and 5 show the position apparatus and one of the connecting cord circuits of one operator's position and indicates the position apparatus and a connecting cord circuit of another position; also 10 one of the called lines with which the cord circuit may be connected. The figures taken together, and arranged side by side in the order indicated by the lines that extend to the margins of the sheets, illustrate as much 15 of a complete organization as is necessary to gain an understanding of the construction and mode of operation of the system.

20 The telephone lines are indicated in each of the two groups shown in Fig. 1, it being understood that each group may comprise a large number of such lines. The practice is to give the finder switch brushes access to 25 the terminals of five hundred lines, these lines being arranged in ten groups of fifty lines each. Each of the lines has associated with it at the central office a line relay 12 and a cut-off relay 11. Each line is also pro- 30 vided with one or more spring-jacks 14 by means of which connection may be made with the line when it is a called line. The lines represented as calling lines in Fig. 1 and the line shown as a called line in Fig. 35 5 may be lines of the same sort, similarly equipped and located at the same exchange; or the lines may be located at different offices. In the present instance, the called line shown in Fig. 5 is indicated as being 40 provided with connections by means of which it may have control over finder switch mechanism in the manner illustrated in connection with the lines of Fig. 1. Each group of lines, LG and LG', has associated with 45 it certain group apparatus consisting of two relays 19 and 24, a common protective relay 250, and a timing sequence switch 100. There is also provided apparatus common to all of the line groups, comprising the 50 relays 22, 23 and 33.

The groups of lines have access to groups of connecting circuits through the medium of finder circuits F, F', F², which terminate upon the brushes of pairs of finder switches 55 of which two sets, LF and CS and LF' and CS', are shown. Each of the groups of connecting circuits is associated with a particular operator's position, of which the apparatus of one is shown at O and the apparatus 60 of the other is partially shown at O'. In the particular system illustrated, it is the practice to provide each operator's position with twenty-five connecting circuits extending to multiple groups of terminals upon 65 the cord selector switches, and to give the

brushes of each cord selector switch access to the terminals of twenty such groups of connecting circuits. But one of the connecting circuits is shown complete, the other connecting circuits in the associated group 70 and in the other groups being similarly organized and connected. Multiple connections of the connecting circuit with the terminals of the cord selector switches are shown in the case of the connecting circuit 75 that is indicated and the one that is completely illustrated; and in like manner multiple connections of the telephone line with the terminals of the line finder switches are shown in the case of the lines that extend 80 from the two stations shown. The multiple connections that exist between corresponding sets of switch terminals and the other connecting circuits and telephone lines are omitted to avoid confusing the drawing. 85 A number of groups of cord selector switches like the group illustrated in Fig. 3 may have access to the same groups of connecting circuits and their corresponding operators' positions. This is indicated in 90 Fig. 3. Each of the groups of cord selector switches has associated with it certain selection controlling apparatus, that associated with the cord selector switches shown in Fig. 3 appearing under the caption 95 "Frame 2", and that associated with the cord selector switches of the other group that is not shown appearing under the caption "Frame 1". The selection controlling apparatus for each frame or group of cord selector switches comprises a set of relays 77, 100 93, and 94 for each operator's groups, CG, CG', to which the cord selector has access, and a group of relays 54, 55, 61 and 63 common to all of the first mentioned groups. 105

As the line finder switches LF and LF', and the cord selector switches CS and CS' in themselves are not novel, they are shown merely diagrammatically. These switches be substantially like the switch illustrated 110 and described in the patent to James L. McQuarrie, No. 1,177,044, issued March 28, 1916. The line finder and cord selector switches are alike in all substantial respects. Each comprises a longitudinally movable shaft 1 carrying as many sets of brushes 2 as there are groups of stationary terminals to be engaged. To move the shaft up, an extension at the lower end of the shaft is brought into engagement with the constantly rotating power member 3 by means of an idler wheel operated by the up-drive magnet 32; and to move the shaft down, the extension is brought into engagement with the power member 4 by means of an idler wheel operated by the down-drive magnet 62. 115

Normally the brushes of each of the sets 2 are held apart, so as to clear the associated terminals, by means of a separating 120 125 130

cam 5 located between the innermost brushes of the set. The cam 5 is rotatably mounted, and when rotated in one direction, releases the brushes and permits them to engage the associated terminals. The tripping or releasing of the brushes is controlled by a number of trip-magnets 16, 17. Each of these when energized rotates an associated trip rod 6 that extends transversely to the switch shafts 1 and carries as many tripping yokes 7 as there are finder switches in the group. The trip rod, in rotating, brings all of its tripping yokes 7 into position to operate the brush controlling cams 5 of the corresponding sets of brushes on all of the switches, so that whichever of the finder switches is caused to move up has that set of brushes tripped that corresponds with the particular trip magnet 16, 17, that is at the time energized. When the finder switch that has been in use is returned to its normal position, any of the associated controlling cams 5 that has been tripped is engaged and rotated in a reverse direction to separate its switch springs again and thus render them inactive.

Each of the line finder and cord selector switches has associated with it a commutator 8 which comprises a number of stationary commutator segments and a set of movable brushes carried at the top of the switch shaft 1 and cooperating with the stationary segments. This commutator serves to make and break a number of controlling circuits in the various stages of the upward movement of the switch shaft.

For controlling the circuits of the organization, there are employed a number of sequence switches which are shown at different points and are designated 100, 200, 300, 400 and 500, respectively. These sequence switches may be of the type disclosed in Patent 1,127,808 issued February 9, 1915, to Reynolds and Baldwin. Each 45 consists of an electromagnetically controlled motor or driving mechanism and a number of associated switch cams. The switch cams associated with each of the sequence switches 100 are designated 101 to 50 103 inclusive; those associated with each of the sequence switches 200 are designated 201 to 223 inclusive; those associated with each of the sequence switches 300 are designated 301 to 310 inclusive; those associated with 55 each of the sequence switches 400 are designated 401 to 416 inclusive, and those associated with each of the sequence switches 500 are designated 501 to 519, inclusive. To each of the contacts associated with the 60 various sequence switch cams are applied certain numerals. These numerals in the case of the cams 101, 201, 301, 401 and 501 indicate the only positions of the associated sequence switch in which these particular 65 contacts are open; the numerals applied to

all of the other contacts of each sequence switch indicate the only positions of the particular associated switch in which the associated contacts are closed.

The sequence switches 100 merely act as timing switches and have only one resting position. The resting positions of the other sequence switches, and the stages of operation with which these positions are associated, are as follows:

75

Sequence switch 200.

1. Normal.
2. Awaiting starting circuit.
3. Awaiting starting circuit release. 80
4. Hunting calling line.
5. A waiting preceding finder circuit.
6. Awaiting operator's selecting circuit.
7. Releasing operator's selecting circuit.
8. Hunting cord circuit. 85
14. Talking.
15. Line finder at tell-tale.
16. Cord selector at tell-tale.
- Line finder return.
17. Cord selector return. 90

Sequence switch 300.

1. Awaiting a call.
4. Position vacant.
17. Position busy. 95

Sequence switch 400.

1. Normal.
7. Listening in.
15. Listening out. 100

Sequence switch 500.

1. Normal.
2. Awaiting listening key sequence switch. 105
- 4
- 5
- 7
- 8 Selective ringing operations.
- 10
- 11
13. Ringing called line. 110
16. Awaiting supervisory relay.
17. Talking.

The manner in which the system is organized will appear from the description of its operation which follows. It will be assumed that the subscriber at station A initiates a call. When the telephone receiver is taken from the switchhook, a circuit is closed that extends by way of both windings of the line relay 12 and both limbs of the telephone line, and is completed in the contacts of the switchhook at the subscriber's station. The flow of current in this circuit energizes the line relay 12, which in operating applies at its right-hand armature and contact, a ground to the conductor 18. This causes current to flow from battery through the winding of the relay 19, sequence switch 130

contact 103 (18 $\frac{1}{4}$ to 1 $\frac{1}{4}$), conductor 18 and ground at the contacts of the operated line relay 12. The relay 19 attracts its armature and closes a circuit that extends from battery through the right-hand winding of the associated relay 24, front contact of relay 19, back contact of relay 22 and lower armature and back contacts of relay 32 to ground. Relay 24 operates and closes at its 10 left-hand front contact a circuit that extends from battery by way of the winding of the associated group trip magnet 16 and the left-hand winding of the relay 24, in parallel, to the front contact of that relay, 15 and thence by way of conductor 58, the winding of the relay 22, and the lower armature and back contact of the relay 23 to ground.

Current flowing in the circuit traced above 20 operates the trip magnet 16 of the group in which the calling line is located, locks up the relay 24 of the associated group and operates the relay 22 common to all of the groups. The trip magnet 16 rotates its associated trip rod to bring all of the yokes into position to trip the corresponding set of brushes of whichever of the line finder switches is started. The group relay 24 breaks, at its left-hand back contact, the 25 circuit of the conductor 58 to the corresponding relays 24 of the succeeding groups of the series.

The relay 24, at its right-hand front contact, also completes a circuit that extends 30 from battery through the motor magnet of the sequence switch 100, and contact 102 (18 $\frac{1}{4}$ to 1 $\frac{1}{4}$) of that switch. In moving out of position 1, sequence switch 100 closes its contact 101 and opens its contact 103. As 35 contact 101 is closed in all positions excepting position 1 of the sequence switch, the switch is caused to make one complete rotation; and as contact 103 of the sequence switch is open in all positions excepting 40 positions 18 $\frac{1}{4}$ to 1 $\frac{1}{4}$, the conductor 18 is held open while the sequence switch is making its revolution and until it gets back to position 1. The time required by the sequence switch to make one complete rotation is so 45 regulated as to be greater than that occupied by the line finder switch in finding the terminals of any calling line. The action, therefore, is such as to interrupt the group conductor 18, and hold it open until after 50 the line relay 12 of the calling line has been released as a result of the finding of that line.

The relay 22, common to all the groups, in 55 operating opens at its back contact the circuit of the conductor 57, which extends serially through the back contacts of the relays 19 of the various groups. As this conductor 57 is the path over which the relay 19 of any group serves to effect the initial energization of the associated relay 24 and the

operation of the corresponding trip magnet, the interruption of this conductor insures the operation of only one trip magnet and the tripping of only one set of brushes on a started line finder switch. 70

The common relay 22, when it operates, applies ground to the starting conductor 29 to start a finder switch hunting for the calling line. The starting conductor 29 has branches extending to like sequence switch 75 cams 206 of all of the finder circuits terminating upon the line finders that have access to the calling line. But, for reasons which will hereinafter be explained, the sequence switch 200 of only one of these finder circuits is standing in its 2 position. Assuming that this is the sequence switch of finder circuit F, when the relay 22 is actuated by the calling line, as already described, a circuit is completed that extends from battery 80 through the left-hand winding of relay 30, sequence switch contacts 206 (2), conductor 29, front contact and armature of starting relay 22, lower armature and back contacts of relay 23 to ground. The right-hand 85 winding of relay 30 is at this time also included in parallel with the left-hand winding of the relay in the energizing circuit, the parallel branch being from battery through resistance coil 56, sequence switch contacts 90 217 (2 to 9) right-hand winding of relay 30, sequence switch contacts 220 (2) and (1 to 13), thereafter joining the conductor that extends from the left-hand winding of relay 30, and to ground over the circuit already 95 traced. The effect of this is to give the relay 30 the benefit of the energizing action of both windings. 100

As a result of the closure of the circuit traced above, the relay 30 is energized and 105 closes a circuit that causes the associated sequence switch 200 to move out of position 2. This circuit extends from battery through the motor magnet of the sequence switch 200, sequence switch contact 202 (2), 110 right-hand front contact and armature of relay 30, sequence switch contact 208 (2 to 7), conductor 79, commutator segment M of the associated cord finder switch CS, and to ground by way of the brush that is in 115 engagement with this commutator segment. Relay 30, in attracting its armatures, also closes a locking circuit for itself that extends from battery by way of the resistance coil 56, sequence switch contacts 217 (2 to 120 9), the right-hand winding of the relay 30, sequence switch contacts 216 (2 to 4) and (2 to 9), front contact and left-hand armature of the relay 30, and armature and back contact of the relay 37 to ground. 125

As a result of the closure of its motor magnet circuit in the right-hand front contact of the relay 30, the sequence switch 200 moves out of position 2 and comes to rest in position 3. In position 3 of the switch, a 130

circuit is closed that extends from battery by way of the up-drive magnet 32 of the corresponding line finder switch LF, conductor 59, sequence switch contact 207 (3 to 4), front contact and right-hand armature of relay 30, sequence switch contact 208 (2 to 7), and to ground by way of conductor 79 and the commutator segment M and associated brush of the corresponding cord 10 finder CS. The energization of the updrive magnet 32 starts the upward movement of the corresponding elevator rod with its associated sets of brushes. At the outset of the upward movement of the elevator rod, 15 all of the brush trip levers are moved past the corresponding trip yokes. The only trip magnet that is energized in this case is the magnet 16 which corresponds with the group in which the calling line is located; and, consequently, the only trip yoke 20 in position to engage a trip lever on the elevator rod is the one which controls the brushes 40, 41, 42 and 43 that are adapted to engage the terminals of that particular 25 group of lines. This set of brushes, therefore, is released and made operative, and the other sets are held clear of their associated line terminals.

As soon as the set of brushes corresponding with the calling line is tripped, the 30 group apparatus, by means of which the lines control the brush tripping and line finder starting operations, may be returned to its normal condition. The first step in 35 this restoring operation is effected by the closure of a circuit which is completed by way of the K segment of the line finder commutator immediately after the brushes are tripped. This circuit extends from battery in parallel branches through the relays 40 23 and 33 (see Fig. 1), conductor 26, sequence switch contact 209 (2 $\frac{1}{2}$ to 3), conductor 45 68, and to ground by way of the K segment of the line finder commutator and its associated brush. The energization of the 50 relay 23 interrupts, at the lower back contact of that relay, the previously described circuit that has up to this time maintained the energization of the trip magnet 16, the 55 group relay 24 and the common starting relay 22. Relay 23, at its upper front contact, closes a locking circuit for itself and the associated relay 33 that extends by way of conductor 25 and the sequence switch contacts 210 (2 $\frac{1}{2}$ to 1) of all of the finder circuits in series, to ground at a point beyond the last switch of the series.

As has already been stated, normally 60 there is only one of the finder circuits with its sequence switch in position 2 awaiting the receipt of a call. When the call comes in, this sequence switch is immediately moved to position 3, in the manner described above. Therefore, at this stage of 65 the operation, the sequence switches of all of

the finder circuits are in position to close their contacts 210. The locking circuit for the relays 23 and 33 is, therefore, held closed until another one of the finder circuits has its sequence switch moved into position 2. This is accomplished by relay 33, which, in operating, applies a ground to conductor 28 to move the sequence switch of another finder circuit out of position 1 and into position 2, and which also applies a ground to the conductor 27 to move the sequence switch of the appropriated finder circuit out of position 3.

Assuming that the sequence switch of finder circuit F' is in position 1 and that 80 the sequence switch of finder circuit F² is in some position between 4 and 17, that finder circuit being assumed to be in use, the operation of the relay 33 completes the following circuit: from battery, through the 85 motor magnet and contact 203 (1) of the sequence switch of finder circuit F', contacts 211 (1) of the same sequence switch, contacts 211 (3 to 17) and (4 to 17) of the sequence switch 200 of finder circuit F², 90 contacts 211 (3 to 17) and (3 to 3 $\frac{1}{2}$) of the sequence switch 200 of finder circuit F, conductor 28, lower contact and armature of the relay 33 to ground. This causes the sequence switch of finder circuit F' to move 95 into position 2.

If by any chance the sequence switch of finder circuit F' should fail to be moved into the call-awaiting position 2 when the relay 33 operates, it will be moved into that position when the sequence switch of the appropriated finder circuit F moves into position 5 at a slightly later stage in the operation. The circuit by which this result would, under the circumstances, be accomplished extends from battery through the motor magnet and contact 203 (1) of the sequence switch of finder circuit F', contacts 211 (1) of that sequence switch, sequence contacts 211 (3 to 17) and (4 to 17) of finder circuit 100 F² (assumed to be in use), and thence by way of contacts 222 (5 to 1) of all of the finder circuit sequence switches in series to ground. In other words, at any time that the finder circuit sequence switches are all 105 standing in position 1 or in position 5 and beyond, a ground is applied by way of the 222 cams in series that moves one of the switches into position 2, and thus places the associated finder circuit in its call-awaiting 110 condition. The sequence switch of finder circuit F is moved out of position 3 by the closure of a circuit that extends from battery through the motor magnet and contacts 203 (3) of the sequence switch of that circuit, conductor 27 and upper contact and armature of relay 33 to ground. As soon as the sequence switch of finder circuit F' moves into position 2, it opens at its contact 115 210 the circuit by way of conductor 25 120

125

130

which has been maintaining relays 23 and 33 energized, and these relays release their armatures. Relay 23, in releasing, reconnects to ground the circuit which extends in branches 57 and 58 through its various sets of group relays, thus again giving the groups access to the starting circuit.

At this stage of the operation of the system, the sequence switch of the appropriated 10 finder circuit F is in position 4, and the elevator rod of the associated line-finder LF is moving up with the set of brushes tripped that corresponds with the group in which the calling line is located. As the tripped 15 brushes rise, they come into engagement successively with the sets of contacts corresponding with the different lines of the group. At the instant of engagement of the brush 43 with the terminal 47 of each line, the test relay 37 of the finder circuit 20 is connected with local conductor 253 of that line. This local conductor has two branches, one or the other of which is closed depending upon the condition of the line relay 12 25 of the associated line. If the line relay is inert, as it is when the line is not calling, or when the line has been connected with and its cut-off relay operated, the local conductor 253 of the line is connected with 30 ground by way of an identifying device 252 and a relatively low potential battery. If the line relay 12 is energized, as it is when the line is calling and is not connected with, the local conductor 253 of the line is connected 35 with ground by way of the right-hand back contact and armature of the protective relay 250 common to a group of lines, the energizing winding of this relay, and a relatively high potential battery 251. Therefore, as the elevator rises and the brush 43 40 engages the corresponding terminal 47 of each of the lines of the group in which the calling line is located, a circuit is completed as each line terminal is engaged that extends, either by way of the low potential battery, 45 the device 252, and the left-hand back contact and armature of relay 12 to the local conductor 253 of the line; or by way of the high potential battery, the winding of common relay 250, the right-hand armature and 50 back contact of that relay and the left-hand front contact and armature of relay 12 to the local conductor 253; and thence by way of line terminal 47, brush 43, conductor 51, 55 finder sequence switch contacts 204 (1 to 8) and (2 $\frac{1}{2}$ to 4), and winding of relay 37 to ground.

The relay 37 is so adjusted that it will respond only to the current flow produced 60 in the circuit by the high potential battery, and not to that produced by the low potential battery. As the line relay 12 of the calling line is energized, thus connecting the high potential battery to the associated local conductor 253, the test relay 37 re-

sponds when the brush 43 engages the terminal 47 of the calling line. The response of the relay 37 causes that relay to interrupt in its back contact the previously traced circuit by way of the left-hand armature and front contact of the relay 30, sequence switch contacts 216, and right-hand winding of relay 30, which circuit had been holding the relay 30 locked up from the moment that the relay was first energized upon the receipt 70 of the call. Relay 30 in releasing its armatures breaks its own locking circuit, and also breaks the previously-traced path, including sequence switch contacts 208, right-hand armature and front contact of the relay 30, 75 and sequence switch contact 207, over which current has been flowing to energize the up-drive magnet 32 of the line finder. Therefore, the operation of the relay 37 upon the finding of the calling line acts to effect the 80 instant deenergization of the up-drive magnet 32, and thus to stop the brushes upon the terminals of the calling line.

In order that the brushes may always be stopped in registration with the line terminals, the locking circuit of the relay 30 has an alternative path to ground by way of sequence switch contact 215 (2 to 4), conductor 66, the C segment of the line finder commutator and the corresponding brush to 90 ground. The C segment of the commutator is so formed and related to its brush that the connection between the two is interrupted only when the corresponding line brushes on the elevator rod are in engagement with corresponding sets of line terminals. The unlocking of the relay 30, and the consequent stopping of the upward movement of the elevator rod, can therefore occur 95 only when the line brushes are in proper relation to the terminals of the calling line.

When the relay 30 is deenergized, as a result of finding the calling line, it also completes a circuit that extends from battery through the motor magnet and contact 202 (3 to 4) of the finder sequence switch, right-hand back contact and armature of the relay 30, sequence switch contact 208 (2 to 7), conductor 79, and M segment and corresponding brush of the cord selector CS to 100 ground. The closure of this circuit moves the sequence switch out of position 4. When the finder sequence switch reaches position 4 $\frac{1}{2}$, it closes a path for the flow of current 105 through the cut-off relay 11 of the calling line by way of resistance coil 64, sequence switch contact 212 (4 $\frac{1}{4}$ to 12 $\frac{1}{2}$), conductor 50, brush 42, line terminal 46 and conductor 53. The flow of current in this circuit operates the cut-off relay 11 to disconnect the 110 relay 12 from the circuit, and that relay in releasing its armatures disconnects the high potential test battery from the local conductor 253 and disconnects ground from the common conductor 18. The disconnection 115 120 125 130

of ground from conductor 18 occurs before the timing sequence switch 100 has completed its cycle of rotation and reconnected conductor 18 with relay 19.

5 The brushes of the line finder switch are now at rest in engagement with the terminals of the calling line, the sequence switch 200 of finder circuit F is at position 6, the group starting circuit represented by the 10 conductors 57 and 58 and the associated relays 22, 23 and 33 has been released and is in readiness to respond to another calling line, and the sequence switch of another finder circuit has been moved into position 2, and 15 thus brought into operative relation with the starting conductor 29.

When the sequence switch of the finder circuit over which the call is being extended has reached position 6, the finder circuit is 20 brought into operative relation with the operators' selecting circuit. When the finder sequence switch reaches position 6, it awaits the closing of a circuit, the completion of which is dependent upon the condition of the other finder circuits of the 25 associated group. This circuit extends from battery through the left-hand winding of the relay 30, contact 219 (6) of the appropriated circuit sequence switch contacts 219 30 (9 to 4) of the sequence switches of the associated finder circuits preceding it in the series, conductor 76, outer armature and back contact of relay 54, and right-hand back contact and armature of relay 61 to 35 ground. A branch path for the energization of relay 30 also exists at this time, this branch path extending from battery through resistance 56, sequence switch contacts 217 (2 to 9), right-hand winding of relay 30, 40 sequence switch contacts 220 (6) and (1 to 13), and contact 219 (6) of the appropriate finder circuit sequence switch, from which point it extends to ground at the right-hand back contact and armature of the 45 relay 61 over the path already traced. This circuit for the energization of relay 30 is open either in the cam 219 of a preceding finder sequence switch in the series, or in contacts of the relay 54 or 61 as long as 50 any sequence switch of the series is in positions 4 to 9. That is, it is open from the time the line finder switch of any associated finder circuit finds a calling line until the cord finder switch of that circuit has moved 55 far enough to trip the brushes corresponding with the selected operator's position, as will be described. Not until this has occurred will the above-traced circuit of the awaiting finder circuit be closed. When the 60 circuit is closed, the relay 30 attracts its armatures and completes a circuit that extends from battery through the motor magnet and sequence switch contact 202 (6 to 7) of the sequence switch 200, right-hand front 65 contact and armature of relay 30, sequence

switch contact 208 (2 to 7), conductor 79, and segment M and corresponding brush of the cord selector commutator to ground. The completion of this circuit moves finder sequence switch out of position 6.

When the sequence switch 200 reaches position 6 $\frac{1}{2}$ it closes a circuit that extends from battery by way of the winding of relay 55 (Fig. 3), conductor 71, sequence switch contact 218 (6 $\frac{1}{2}$ to 8), conductor 67, and segment M and corresponding brush of the line finder commutator to ground. The operation of the relay 55 applies ground to the conductors 81 extending to all of the operators' positions. At each of the positions 80 where the operator is at her station and is in readiness to receive a call, the associated relay 91 (Fig. 4) is inert, and the operator's telephone sequence switch 300 is in its 1 position. Consequently at each of such positions, a circuit is closed that extends from battery, through the winding of the associated relay 92, left-hand armature and back contact of relay 91, sequence switch contact 304 (1), conductor 81, armature and front 90 contact of relay 55 to ground. The relay 92 of each available position therefore attracts its armature and closes a circuit that extends from battery, through the front contact and armature of the relay 92 to the conductor 95 82, and thence to ground by way of the windings of the relays 77 corresponding to that operator's position at the various cord selector frames.

When the finder sequence switch 200 reaches position 7, in which position it comes to rest, it closes a circuit that extends from battery through the winding of relay 54, left-hand back contact and armature of relay 61, conductor 73, finder sequence switch 105 contact 218 (7 to 8), conductor 67, and segment M and corresponding brush of the line finder commutator to ground. Relay 54 attracts its armatures and completes a branch of the circuit traced above, which branch 110 extends from conductor 73 by way of the armature and back contact of the relay 63, front contact and inner armature of relay 54, armature and front contact of relay 77 (which relay is energized, as previously described, as a result of the corresponding operator's position being in readiness to receive a call), right-hand back contact and switch spring of relay 93 of the corresponding group, winding of associated relay 94, 115 winding of relay 93, left-hand switch spring and resting contact of relay 93, conductor 83, left-hand back contact and armature of relay 95 at the 0 operator's position to battery. Upon the closure of the above-traced 120 branch circuit, group relays 93 and 94 are energized in parallel with the relay 54. Relay 93 in operating disconnects its own energizing winding and that of relay 94 from the previously traced path to battery by 130

way of the left-hand back contact and armature of relay 95, and connects them in a path which extends to battery by way of conductor 84 and the winding of the relay 95. This causes the relay 95 also to be energized and to interrupt in its left-hand armature and back contact the path by way of conductor 83 over which the relays 93 and 94 were initially energized.

- 10 Relay 94 in operating closes a circuit from battery through the winding of the trip magnet 20 corresponding to the selected operator's position, and to ground by way of the right-hand armature and front contact 15 of the relay 94. This relay also closes a circuit that extends from battery through the winding of the relay 63 and the left-hand armature and front contact of the relay 94 to ground. The relay 63 in operating closes 20 a branch that extends from the conductor 73 (grounded by way of contact 218 (7 to 8) of the line finder sequence switch) through the armature and front contact of relay 63, conductor 72, sequence switch contacts 220 25 (7) and (1 to 13), and left-hand winding of relay 30 to battery. A branch energizing path for relay 30 also extends from conductor 72 by way of sequence switch contact 220 (7), right-hand winding of relay 30, sequence switch contacts 217 (2 to 9), and resistance 56 to battery. Relay 30 attracts its armatures and closes a circuit that extends from battery through the motor magnet and sequence switch contact 202 (6 to 7), 30 front contact and right-hand armature of relay 30, sequence switch contact 208 (2 to 7), conductor 79, and segment M and corresponding brush of the cord selector commutator to ground. The closure of this circuit moves sequence switch 200 out of position 35 7. Furthermore, relay 30 in operating is locked up over a circuit that extends from battery through resistance 56, sequence switch contacts 217 (2 to 9), right-hand 40 winding of relay 30, sequence switch contacts 216 (7 to 9) and (2 to 9), front contact and left-hand armature of relay 30 and armature and back contact of relay 37 to ground. When the sequence switch reaches 45 position 8 it closes a circuit that starts the upward movement of the brush-carrying rod of the cord selector switch, this circuit extending from battery through the up-drive magnet 34 of the cord finder, conductor 89, 50 sequence switch contact 207 (8 to 9), right-hand front contact and armature of relay 30, sequence switch contact 218 (8 to 9), conductor 67, commutator segment M of the line finder and corresponding brush to 55 ground.

60 At the outset of the upward movement of the cord finder brush rod, the tripping levers of the various sets of brushes are brought simultaneously into operative position with 65 respect to the corresponding tripping yokes,

and that set of brushes is tripped and made operative whose trip magnet is at the time energized. In the present instance, it is assumed that this is the trip magnet 20 associated with the terminals of the group of 70 connecting cord circuits extending to the O operator's position. Immediately after the set of brushes is tripped, the common operator's selecting circuit is restored so as to be available for the use of other cord finder 75 switches. This is effected through the medium of a circuit that is completed by the grounding of the K segment of the cord finder commutator, this segment being so located as to be engaged by its brush immediately after the tripping levers of the sets of brushes pass the associated tripping yokes. The circuit referred to extends from battery through the winding of relay 61, conductor 74, sequence switch contact 221 80 (7 $\frac{3}{4}$ to 8), conductor 80, cord finder commutator segment K and its corresponding brush to ground. Relay 61 in operating opens, at its left-hand back contact, the previously-traced circuit by way of conductor 90 73 which, up to this time, has been holding energized the relay 95 at the O operator's position and the relays 93 and 94 for responding to this position on the cord finder frame. The release of the relay 94 deenergizes the corresponding trip magnet 20 and the common relay 93 95. The deenergization of the relay 93 reestablishes, subject to the release of relay 61, the control of other finder circuits over the brush tripping mechanism of the associated cord finder frame. Relay 61, in operating, closes a locking circuit for itself by way of conductor 73, sequence switch contact 218 (7 to 8), conductor 67, commutator segment M of the line finder and corresponding brush to ground. It also completes a circuit that extends from battery through the motor magnet and contact 205 (8) of the sequence switch 200, conductor 75, right-hand front contact and armature of relay 61 to ground. The closure of this circuit moves sequence 100 switch 200 out of position 8. In moving out of position 8, the sequence switch opens its contacts 218 (7 to 8), thus deenergizing relay 61 and again extending conductor 73 to the relay 54 and the conductors over which the operator's selection is effected. In closing its right-hand back contact upon release, relay 61 also restores the continuity of conductor 76 and makes it available for moving out of position 6 the sequence switch of some other finder circuit which may be waiting for access to the operator's selecting circuit.

110 After the cord selector switch CS passes the brush-tripping position, it continues its upward movement until the brushes are stopped by engaging the terminals of one of the connecting circuits that is not in use. The idle or busy condition of the connecting 115 120 125 130

circuit is indicated by the presence or absence of high-potential battery on the test terminal 118 of each connecting circuit. When the brushes engage the terminals of an idle connecting circuit, a path for the flow of current is completed from high potential battery 251 (see Fig. 4), through the winding of common protective relay 197, armature and back contact of that relay, 5 lower back contact and armature of relay 134, conductor 128, right-hand armature and back contact of relay 119, lower back contact and armature of relay 155, contact 404 (1) of the listening key sequence switch, 10 conductor 88, test terminal 118 and brush 114 of the cord selector, conductor 99, finder sequence switch contacts 206 (8 to 9) and the winding of relay 37 to ground. Relay 37 thereupon attracts its armature and opens 15 the previously traced locking circuit that has been holding relay 30 energized. Relay 30, in releasing its armatures, opens at its right-hand front contact and armature the energizing circuit for the up-drive magnet 20 34, thus stopping the brushes of the cord selector switch in engagement with the terminals of the selected connecting circuit. In engaging its back contact, the right-hand armature of relay 30 closes an energizing 25 circuit for the motor magnet of the finder sequence switch which extends by way of cam 202 (8 to 9), back contact and right-hand armature of relay 30, cam 218 (8 to 9), conductor 67, and the M segment and corre- 30 sponding brush of the line-finder commuta- 35 tor to ground. The closure of this circuit moves sequence switch 200 out of position 9, whereupon the switch continues to move until it reaches position 14, where the talk- 40 ing circuit is completed at cams 213 and 214.

An instant after the finder sequence switch leaves position 9, it closes a circuit that extends from battery through the windings of 45 relays 151 and 154 (see Fig. 5) in parallel, connecting cord sequence switch contact 505 (1), listening key sequence switch contact 405 (1), left-hand back contact and armature of relay 152, conductor 87, cord selector 50 switch terminal 117 and corresponding brush 113, conductor 98, and finder sequence switch contacts 217 (9 $\frac{1}{4}$ to 14) and (9 $\frac{1}{4}$ to 11) to ground. Relay 154 in operating 55 closes a locking circuit for itself and relay 151 that extends by way of its left-hand front contact and armature, connecting cord sequence switch contact 506 (1) and listening key sequence switch contact 406 (1 to 6) to ground. Relay 154 also closes a circuit 60 that extends from battery through the motor magnet and cam 403 (1) of the listening key sequence switch, contacts 507 (17 to 8) and (1) of the connecting cord sequence switch and right-hand front contact and 65 armature of relay 154 to ground. The

closure of this circuit causes the listening key sequence switch to move out of position 1, and, in doing so, to open the test conductor 88 at sequence switch contact 404 (1), and also to open at sequence switch contact 70 405 (1) the path over which the relays 151 and 154 were first energized.

Relay 151, associated with relay 154, in operating closes a circuit that extends from battery through the winding of relay 152 75 and outer front contact and armature of relay 151 to ground. As a result relay 152, prior to the moving of the listening key sequence switch out of position 1, has disconnected conductor 87 from connection with 80 battery by way of sequence switch contact 405 (1) and the windings of relays 151 and 154, and has connected it with an alternative path to battery by way of the left-hand front contact of relay 152 and winding of 85 relay 155. The relay 155 in operating closes at its upper front contact and armature a normal break in talking conductor 86, and at its lower back contact and armature opens the path of test conductor 88. When 90 the listening key sequence switch reaches position 2, an additional path to ground for holding the relay 152 energized, is closed by way of sequence switch contact 407 (2 to 7).

The energization of relay 151 at the instant the cord is seized also brings about the closure of a circuit that extends from battery through the winding of the common relay 134, conductor 129, contact 502 (1) of the connecting cord sequence switch, and inner front contact and armature of relay 151 to ground. Relay 134 in operating opens at its lower armature and back contact the circuit over which the potential of the high voltage test battery 251 is applied to the test 100 conductors 128 of all of the connecting cords of the position. Thus the electrical condition which permits a connecting cord to be seized by a cord selector is withdrawn from the selected cord and also from its associated 105 110 cords at the instant of seizure, and is not reapplied to such of the cords as may be in condition to be selected until the common relay 134 is deenergized. The deenergization of relay 134 occurs when the relays 151 115 and 154 are released by the opening of their locking circuit at cam 406 when the listening key sequence switch moves beyond position 6.

When the listening key sequence switch 400 is moved out of position 1, in the manner described above, it continues its movement until it reaches position 7. In position 7 the cams 408, 409, 410 and 411 of the listening key sequence switch interrupt the talking strands of the connecting circuit and 120 include between their severed ends a loop that has connection by way of conductors 135 and 136 with the operator's telephone set 147. This puts the operator in communication with the calling subscriber. At the 130

same time the operator is informed of the identity of the connecting cord over which the call is being extended by the flashing of the lamp 161 associated with that cord, the 5 circuit for illuminating this lamp extending from battery through the resistance 163, lamp 161, calling cord sequence switch contact 514 (1 to 2), listening key sequence switch contact 412 (1 $\frac{1}{4}$ to 18 $\frac{1}{4}$), and inter-
10 rupter 162 to ground.

As has previously been explained, when the sequence switch of an appropriated finder circuit reaches position 6 $\frac{1}{2}$, it operates a trip magnet on the cord selector frame 15 that corresponds with a waiting operator's position, and at the same time operates the relay 95 associated with the apparatus at that operator's position. When the relay 95 at the operator's position attracts its armatures, it closes a circuit which extends from battery through the winding of the relay 142, conductor 121, right-hand front contact and armature of relay 95, and right-hand front contact and armature of relay 125 to 20 ground. Relay 142 in operating closes a locking circuit for itself that extends to ground by way of the inner front contact and armature of relay 142, operator's sequence switch contact 305 (16 $\frac{1}{4}$ to 15) and 25 the right-hand front contact and armature of relay 125. The relay 142 in operating also closes a circuit that extends from battery through the motor magnet and contact 303 (1) of the operator's sequence switch, 30 outer front contact and armature of relay 142, contact 306 (1 to 9) of the operator's sequence switch and right-hand front contact and armature of relay 125 to ground. The closure of this circuit causes the operator's sequence switch to move out of position 35 1 and to continue its movement until it comes to rest in position 17. By causing the relay 95 to control the movement of the operator's sequence switch 300 out of position 40 1 through the medium of the locking relay 142, this movement of the operator's sequence switch is made certain, even though there is only a momentary energization of the relay 95 in the selection of the operator's position. As the locking circuit of the 45 relay 142 is controlled in the contact 305 (16 $\frac{1}{4}$ to 15) of the operator's sequence switch, the locking circuit is broken and the relay 142 released the moment the sequence switch 300 passes beyond position 15 in its 50 movement to its resting position 17.

The left-hand winding of the relay 91 is connected in parallel with the winding of the relay 142; and as a result the instant relay 95 attracts its armature, the relay 91 opens, at its left-hand armature and back contact, the path over which the relay 92 is energized when the operator's position is to be selected. This path is also opened at 55 sequence switch contact 304 (1) an instant

later when the operator's sequence switch is moved out of position 1 by the energization of the locking relay 142. Thus the operator's position is made inaccessible to other calls the instant it is selected, and is maintained inaccessible until the operator's sequence switch returns to position 1 and the relay 91 is deenergized. 70

When the relay 95 operates upon the selection of the operator's position, it closes a 75 circuit that extends from battery by way of the left-hand armature and front contact of relay 95, conductor 120, and thence through two parallel paths, one of which extends through the winding of the relay 195 and the right-hand front contact and armature of relay 125 to ground, and the other of which extends through the winding of the relay 145, upper back contact and armature of relay 153, operator's sequence switch contact 302 (18 $\frac{1}{4}$ to 15) and the right-hand front contact and armature of the relay 125 to ground. The relay 145 in operating closes at its front contact and armature an alternative path for supplying current for maintaining the energization of the relays 145 and 195 after the relay 95 has released its armatures at the conclusion of the selecting operation. The relay 195 in operating effects certain circuit changes the object of 80 which will be described hereinafter. The relay 145 in operating closes a circuit that extends from a source of call-tone current 143 through a condenser 144, right-hand front contact and armature of relay 145, and a winding of the operator's induction coil 146 to ground. Thus a call-tone is produced in the operator's telephone receiver the instant the relay 95 operates upon the selection of the position. As the energizing circuit 85 for the relay 145 which controls the application of the call-tone is controlled at the upper back contact and armature of relay 153 and at the operator's sequence switch contact 302 (18 $\frac{1}{4}$ to 15) the call-tone continues 90 until the relay 153 is energized, or until the operator's sequence switch, which is independently actuated by the relay 95 at the instant of selection, as has been described, moves past position 15 in its movement from 95 position 1 to position 17. 100

The energization of the relay 153 is effected by the closure of the circuit that extends from battery through the winding of the relay 153, conductor 129, and upper front contact and armature of relay 134 to ground. The relay 134, as has already been described, is energized by the energization of the relay 151 at the moment the circuit by way of conductor 87 is closed upon the seizure of the 105 connecting cord of the cord selector switch. Thus the relay 153 is energized to deenergize the relay 145 to withdraw the call-tone upon the seizure of the connecting cord at the selected operator's position. As the continued 110

energization of the relay 195 is under the control of the relay 145, the relay 195 is also released by the operation of the relay 153 upon the seizure of the cord.

5 From the foregoing description it may be seen that the operator is given a preliminary warning of the selection of her position by hearing the call-tone in her telephone receiver, and that a few moments later she is 10 apprised of the connecting cord that is to be used by the flashing of the lamp 161 associated with that cord. In the meanwhile the position has been made inaccessible to other incoming calls by the operation of the relay 15 91 and the movement of the operator's sequence switch 300 out of position 1, and the operator's telephone apparatus has been connected with the selected connecting cord by the movement of the connecting cord sequence switch to position 7. The operator 20 now being in communication with the calling subscriber, inquires the number of the line that is wanted, and upon being informed completes connection with that line by inserting the calling plug 170 into the corresponding spring-jack 14, first testing the line by touching the tip of the plug to the sleeve of the spring-jack. If the line is busy, 25 the potential that exists upon the sleeve of the spring-jack causes current to flow by way of the tip of the plug, the right-hand armature and back contact of relay 175, conductor 133, and winding of relay 184 to ground. Relay 184 in operating closes a 30 circuit that extends from battery through the retardation coil 185 and the test winding of the operator's induction coil 146 to ground. This causes a click in the operator's telephone receiver that tells her that the line is 35 busy. Assuming that the line is free for connection, the insertion of the plug 170 closes a circuit that extends from battery through the coils of the relays 119 and 175 in series, and thence by way of the registering sleeve contacts of the plug 170 and 40 spring-jack 14 to ground by way of the winding of the cut-off relay 11. The cut-off relay 11 disconnects the line relay 12 from the circuit. The relay 175, at its right-hand 45 armature and back contact disconnects the tip of the plug from the conductor 133 extending to the operator's busy test relay 184, and connects it instead with the tip strand of the talking circuit. Relay 175 also closes 50 a circuit that extends from battery through the motor magnet and contact 503 (1) of the calling cord sequence switch, contact 418 (7) of the listening key sequence switch, and left-hand front contact and armature of 55 relay 175 to ground. The closure of this circuit energizes the motor magnet and moves the call cord sequence switch out of position 1. When the calling cord sequence switch reaches position 2 it comes to rest and completes a circuit that extends from battery

through the motor magnet and contact 403 (7) of the listening key sequence switch, contact 515 (2) of the calling cord sequence switch, and right-hand back contact and armature of relay 154 to ground. When the 70 listening key sequence switch 400 moves out of position 7 as the result of the closure of this circuit, it completes a circuit that extends from battery through the motor magnet and contact 504 (2) of the calling cord 75 sequence switch, contact 413 (8 to 15) of the listening key sequence switch, and left-hand front contact and armature of relay 175 to ground. The closure of this circuit moves the calling cord sequence switch out of position 80 2.

As the listening key sequence switch 400 moves beyond position 8, it operates its cams 408, 409, 410 and 411 to disconnect from the connecting cord circuit the loop that extends to the operator's telephone circuit by way of the conductors 135, 136, 165 and 166 and connects the talking conductors 85 and 86 of the connecting cord circuit directly through to the left-hand windings of the repeating coil 90 169. Furthermore, it interrupts the branch of the energizing circuit of the cord circuit holding relay 152 that had been completed to ground by way of listening key sequence switch contact 407 (2 to 7) and leaves the 95 continued energization of the holding relay dependent upon a path to ground that extends by way of the right-hand front contact and armature of relay 152 and contact 508 (1 $\frac{1}{2}$ to 18 $\frac{1}{2}$) of the calling cord sequence 100 switch.

After the calling cord sequence switch 500 is moved out of position 2 by the movement of the listening key sequence switch out of position 7, as described above, it moves 105 through its various stages (under the control of the circuit which extends to ground by way of calling cord sequence switch contact 504 (4 to 13) and the right-hand back contact and armature of relay 180) until it 110 reaches position 12, at which point a circuit is closed that extends from battery through the winding of relay 180, left-hand armature and back contact of relay 178, armature and back contact of relay 177, sequence 115 switch contacts 507 (12 to 13) and (10 to 15), and sequence switch contact 516 (3 to 13) to ground. The closure of this circuit energizes relay 180 and causes it to open at its right-hand armature and back contact 120 the circuit by way of contact 504 (4 to 13) of the calling cord sequence switch which theretofore had maintained the energization of the motor magnet of that switch. As the cam 501 of the calling cord switch is cut so 125 as to keep the energizing circuit of the motor magnet closed in position 12 of the sequence switch, the switch continues to move until it reaches position 13, where it comes to rest.

In position 13 of the calling cord sequence switch, ringing current is applied to the connecting cord circuit to ring the bell at the called subscriber's station. This is effected 5 through the medium of a circuit which has two branches alternately closed in the rotation of the commutator 182, one of the branches including the battery and the other including a source of ringing current 181. 10 From the commutator 182 the circuit extends by way of sequence switch contact 517 (13), winding of relay 177, left-hand armature and front contact of relay 180, sequence switch contact 519 (13), ring contact of the 15 calling plug 170, ring spring of the spring-jack 14, and thence over the corresponding side of the line to the called subscriber's station and to ground by way of the sub-station condenser and bell. At the same time the 20 other side of the called subscriber's line is connected directly to ground by way of sequence switch contact 518 (13). The closure of this circuit causes the bell at the sub-station to ring intermittently, and also by the 25 diversion of a small part of the alternating current by way of the condenser 183 and the winding of the repeating coil 169, causes the ringing current to be heard by the calling subscriber. When the called subscriber in 30 responding to the ringing of the bell takes his telephone receiver from its hook, the resultant closure of the relatively low resistance path across the limbs of the line causes an increase in the current flow over the circuit just traced, and brings about the energization of the relay 177. This relay is preferably so constructed and adjusted, in any well known way, as to make it insensitive to the alternating current flow that passes 35 40 through it during the ringing of the bell but responsive to the current flow that takes place when the telephone receiver is taken from its hook.

When the relay 177 operates, it opens the 45 short circuit that normally exists about the winding of the relay 178, which relay is included in the path previously traced through the relay 180 and cams 507 and 516 of the calling cord sequence switch. The removal 50 of the short circuit causes relay 178 to attract its armatures. The opening of the left-hand armature and back contact of the relay 178 prevents the reestablishment of the short circuit about the relay 178 when the armature of relay 177 falls back after a momentary attraction. Engagement of the right-hand armature of relay 178 with its front contact closes a path from battery including 55 a resistance coil 179, which path is in parallel with the path from battery including the relay 180. The resistance of the coil 179 and the winding of the relay 180 are so proportioned that the relay 180 is shunted and releases its armatures. The left-hand armature of relay 180 in falling back opens the 60

previously traced path over which ringing current was applied to the connecting cord circuit. The right-hand armature of relay 180, in releasing and closing its back contact, closes a circuit that extends from battery through the motor magnet and contact 504 (4 to 13) of the calling cord sequence switch. This causes the sequence switch to move out of position 13. 70

When the calling cord sequence switch 75 leaves position 13, it moves to position 16. In this position a circuit is completed that extends from battery through the lower right-hand winding of the repeating coil 169, calling supervisory relay 187, sequence 80 switch contact 519 (16 to 17), engaging ring contact surfaces of the calling plug 170 and called line spring-jack 14, thence to the called subscriber's station over one limb of the line, through the sub-station apparatus 85 and back over the other limb of the line to the engaging tip contact surfaces of the spring-jack 14 and calling plug 170, right-hand armature and front contact of relay 175, sequence switch contact 518 (14 to 17) 90 and upper right-hand winding of the repeating coil 169 to ground. The current flow in this circuit energizes the calling supervisory relay 187 and causes it to close a circuit that extends from battery through 95 the motor magnet and contact 503 (16) of the calling cord sequence switch, and armature and front contact of relay 187 to ground. This moves the sequence switch out of position 16, whereupon it moves to 100 position 17, which is the talking position.

Up until this moment, the lamp 161, which, as described, was caused to flash when the call first came in, has been burning steadily as a ringing lamp, the circuit 105 for its illumination being to ground by way of contact 516 (3 to 16) of the calling cord sequence switch. When the sequence switch moves out of position 16, this circuit is interrupted and lamp 161 is extinguished. At 110 the same time, a circuit is closed from battery through resistance coil 188, and thence by way of two branches, one of which extends through the calling supervisory lamp 189, left-hand front contact and armature 115 of relay 119 and sequence switch contact 513 (17) to ground, and the other of which extends by way of resistance coil 190, sequence switch contacts 514 (17), and armature and front contact of relay 187 to 120 ground. The resistance in the latter branch is low, as a result of which the calling supervisory lamp 189 is shunted out as long as the calling supervisory relay 187 is energized. 125

When this stage has been reached in the operation of the system, the talking circuit is complete between the calling subscriber and the called subscriber, the finder circuit sequence switch 200 is in position 14, the 130

calling cord sequence switch 500 is in position 17, and the listening-key sequence switch is in position 15, the listening out position. In this condition of the circuit, 5 the calling subscriber has control over the answering supervisory lamp 172 through the medium of the answering supervisory relay 171, and the called subscriber has control over the calling supervisory lamp 189 10 through the medium of the calling supervisory relay 187. As long as both subscribers have their telephone receivers off the switchhooks, these lamps are dark. When either one of the subscribers hangs 15 up, the corresponding lamp is lighted. When both lamps light at the same time, the operator knows that the conversation is at an end and takes down the connection.

The operator disconnects by removing the 20 calling plug 170 from the spring-jack of the called subscriber's line. This act permits relays 119 and 175 of the connecting cord circuit and the cut-off relay 11 of the called subscriber's line to fall back. The cut-off 25 relay 11, in falling back, reconnects the line relay 12 with the called subscriber's line. Relay 119 in releasing its right-hand armature reconnects the high potential battery 251 with the test conductor 88 of the cord 30 circuit. But the continuity of the connection of the test conductor 88 with battery is not entirely established, and the cord circuit is therefore not made selectable until the relay 155 has released its armatures and 35 the listening sequence switch contact 404 has been closed by the return of the sequence switch to position 1. The relay 155 at its lower armature opens the test conductor 88 while the talking circuit is established and thus prevents any possible interference of the high potential test battery 251 with the set of class of service impulses common to the exchange. The other armature of the relay 119, in disengaging its 40 front contact, extinguishes the calling supervisory lamp 189.

Relay 175 in releasing completes a circuit that extends from battery through the winding of relay 157, sequence switch contacts 50 512 (2 to 17), and left-hand back contact and armature of relay 175 to ground. Relay 157 in operating closes a locking circuit for itself that extends by way of sequence switch contacts 512 (2 to 17), inner armature and front contact of relay 157, and sequence switch contact 510 (2 to 17) to ground. Relay 157 also closes a circuit that extends from battery through the motor magnet and contact 503 (2 to 17) of the 55 calling cord sequence switch, outer front contact and armature of relay 157, and sequence switch contact 511 (2 to 18) to ground. The closure of this circuit moves the calling cord sequence switch 500 out of 60 position 17, whereupon it continues to rotate

until it reaches and comes to rest in position 1, its normal position.

An instant after leaving position 17, the sequence switch 500 opens, at its contact 508 (14 to 184), the path over which, up to this 70 time, the holding relay 152 has been maintained energized. The relay 152 releases its armatures and brings about the return to normal of the finder circuit and its associated apparatus in a manner presently to 75 be described. When the calling cord sequence switch 500 reaches position 1, it completes a circuit that extends from battery through the motor magnet and contact 403 (15) of the listening-key sequence switch, 80 contact 515 (1) of the calling cord sequence switch and right-hand back contact and armature of relay 154 to ground. This moves the listening-key sequence switch 400 out of position 15 and permits it to return 85 to normal under the control of its cam 401.

When the holding relay 152 of the connecting cord circuit becomes inert, it breaks at its left-hand armature and front contact the circuit by way of conductor 87 of 90 the connecting cord circuit, conductors 98 and 50 of the finder circuit and conductor 53 of the calling line, including windings of relays 155 of the cord circuit, 30 of the finder circuit, and 11 of the calling line. 95 Consequently these three relays release their armatures. The cutoff relay 11 of the calling line in releasing its armatures reconnects the line relay 12 with the line conductors 38 and 39. Relay 30 of the finder circuit in releasing closes a circuit from battery through motor magnet and cam 202 (14) of the finder sequence switch, left-hand back contact and armature of relay 30, 100 and armature and back contact of relay 37 to ground. This moves the finder sequence switch out of the talking position 14. When the finder sequence switch reaches position 15 a circuit is closed for the energization of the relay 30 that includes in parallel 110 branches both windings of that relay. One branch of this circuit extends from battery through resistance 56, sequence switch contacts 217 (15 to 16) and (12 to 16), right-hand winding of relay 30, sequence switch 115 contacts 220 (15) and (11 to 16) to conductor 67; the other branch extends from battery, through the left-hand winding of relay 30, and sequence switch contacts 220 (15) and (11 to 16) to conductor 67; thence both 120 branches extend by way of conductor 67, and M segment and corresponding brush of the line-finder commutator to ground. Relay 30 in operating closes a branch path to ground for maintaining its energization, this 125 path extending from the right-hand winding of relay 30, by way of sequence switch contacts 216 (15 to 16), left-hand front contact and armature of relay 30, and armature and back contact of relay 37 to ground. 130

Relay 30 in operating also closes a circuit that extends from battery, through motor magnet and contact 202 (15) of the finder sequence switch, right-hand front contact 5 and armature of relay 30, sequence switch contact 218 (15), conductor 67, and M segment and corresponding brush of the line-finder commutator to ground. The completion of this circuit energizes the finder sequence switch 200 and causes it to move its 10 cams to position 16.

In moving out of position 15 the sequence switch opens at its 220 cam the branch of the energizing path that includes the left-hand winding of relay 30, and also opens the path to ground by way of conductor 67 15 and the M segment of the line-finder commutator; the energization of the relay being maintained in position 16 of the sequence 20 switch by way of the branch that includes its right-hand winding, cam 216, left-hand contacts of relay 30, and resting contacts of relay 37. This circuit is held closed and relay 30 is kept energized until the cord 25 circuit through which the call was extended has returned to its normal condition. When this occurs a circuit is closed that extends from high-potential battery 251, through the winding and contacts of common relay 197 30 (see Fig. 4), armature and back contact of relay 134, conductor 128, armature and back contact of relay 119, lower back contact and armature of relay 155, sequence switch contacts 404 (1), closed when the cord circuit 35 returns to normal, conductor 88, cord selector contact 118 and corresponding brush 114, conductor 99, sequence switch contact 208 (16), right-hand armature and front contact of relay 30, sequence switch contacts 40 204 (9 to 17) and (16), and winding of relay 37 to ground. The closure of this circuit energizes relay 37, which attracts its armature and opens the previously traced holding circuit of the relay 30. Relay 30 in 45 releasing its armatures closes a circuit that extends from battery through the winding of down-drive magnet 62 of the line-finder switch, conductor 60, sequence switch contacts 223 (16 to 16½) and (16 to 7), left-hand back contact and armature of relay 30, 50 and armature and back contact of relay 37 to ground (the energizing circuit of relay 37 having been interrupted at the right-hand front contact and armature of relay 30 when that relay released). As a result of the closure of this circuit, the brushes of the line-finder switch are returned to normal. As the line-finder brushes reach normal, a circuit is closed that extends from battery 55 through the motor magnet and contact 205 (16) of the finder sequence switch, conductor 69, and Y segment and corresponding brush of the line-finder commutator to ground. When the finder sequence switch moves to 60 position 17, as a result of the closure of the

above traced circuit, a circuit is completed that extends from battery through the winding of the down-drive magnet 35 of the cord selector, conductor 90, finder sequence switch contact 218 (17), conductor 67, 70 and M segment and corresponding brush of the line-finder commutator to ground. The closure of this circuit returns the cord selector switch to normal; and as the brushes reach normal, a circuit is closed that extends from battery through the motor magnet winding and contact 205 (17) of the finder sequence switch, conductor 31, and Y segment and corresponding brush of the cord selector commutator to ground. The closure of this circuit causes the finder sequence switch 200 to return to its normal position. 75 As has hereinbefore been explained, the operator's position is selectable by an incoming call only when the operator's sequence switch 300 is standing in position 1. When the relay 95 is energized upon the selection of the position, the operator's sequence switch is moved to position 17, in the manner hereinbefore explained, and thereafter 80 remains in that position until it is returned to position 1. The circuit for returning the operator's sequence switch from position 17 to position 1 extends from battery through the motor magnet and contact 303 (17) of the operator's sequence switch, and is completed to ground by way of the upper armature and front contact of the relay 192 of the associated position when that relay is 85 operated. The energizing circuit of each of the relays 192 at the various operators' positions extends from battery through the winding and lower switch spring and resting contact of that relay, the right-hand armature and back contact of the associated relay 91, and contact 307 (15 to 18) of the associated operator's sequence switch to a conductor 140 which is common to the energizing circuits of all of the positions, this conductor 140 extending to ground by way of 95 the series of operators' sequence switch contacts 308 (2 to 18) one of which is associated with the sequence switch of each operator's position. Consequently when the sequence switches 300 of the entire series of operators' 100 positions have been advanced to position 2 or beyond by the selection of these positions by incoming calls, or otherwise, as will be explained, the path to ground by way of the conductor 139 is closed, all of the relays 192 105 the paths of which are completed to the conductor 140 are energized, and the operators' sequence switches at such positions are moved out of position 17 and come to rest in 110 position 1. Thus these positions are again 115 rendered available for receiving incoming calls. In order to insure the closure of the energizing circuit of relay 192 for a sufficiently long interval to effect the movement of the associated sequence switch, the relay 120 125 130

in operating closes a locking circuit for itself to ground by way of operator's sequence switch contact 310 (15 to 8), this locking path being opened to release the relay when 5 the sequence switch moves beyond position 18.

It may at times be necessary for the operator to supervise or listen in on an established connection. In order that the operator may 10 bring her telephone apparatus into connection with a circuit upon which connection has been established, it is necessary that the associated listening key sequence switch 400 be moved from its listening-out position 15 15 to its listening-in position 7. This is accomplished by pressing the associated listening-in key 191, which closes a circuit that extends from battery through the motor magnet and contact 402 (15) of the listening key sequence switch, right-hand contact and switch spring of listening-in key 191, conductor 130, right-hand armature and back contact of relay 195, right-hand back contact and armature of relay 95, and right-hand front contact and armature of relay 125 to ground. As a result of the closure of this circuit the listening key sequence switch moves out of position 15. Upon reaching 20 position 1, it is moved through this position 25 by a circuit that extends from battery through the motor magnet and contact 402 (1) of the listening key sequence switch, and contacts 511 (2 to 18) of the calling cord sequence switch to ground. Consequently 30 the listening key sequence switch continues to move until it reaches position 7, in which position the operator's telephone apparatus is again connected with the circuit through the medium of the listening key sequence switch cams 408, 409, 410, 411. Having supervised the connection, the operator may disconnect her telephone apparatus from the circuit by pressing the listening-out key 186, which is common to all of the 35 connecting circuits of her position. This closes a circuit that extends from battery through the motor magnet and contact 403 (7) of the listening key sequence switch, and contacts of the master listening-out key 186 40 to ground. As a result the listening key sequence switch is caused to move out of position 7 and again come to rest in position 15. Or the operator may listen out on one connection by listening in on another. This is 45 effected through the multiple connections which exist between the contacts 402 (7) and the contacts 406 (2 to 6) of all of the listening key sequence switches. When any listening key sequence switch is standing in 50 position 7, the movement of the listening key sequence switch of any other connecting circuit through positions 2 to 6 affords an energizing path to ground for the motor magnet of the listening key sequence switch 55 that is standing in position 7.

When the operator presses a listening-in key 191 to supervise the connection established on the corresponding circuit, it is desirable that in doing so that she shall render her position unselectable by an incoming 70 call if her sequence switch 300 is standing in its waiting position 1; and also, if her sequence switch is standing in position 17, that she shall prevent it from being returned to position 1 by relay 192, as described, in which position the operator's position would again be selectable. To accomplish this, the depression of the listening-in key 191 completes a circuit that extends from battery through the left-hand winding 75 of relay 91, left-hand armature and back contact of relay 195, conductor 138, listening key sequence switch contact 414 (9 to 16) and left-hand contact and switch spring of the listening-in key 191 to conductor 130, 80 from which point the path to ground is as has already been traced. If the operator's sequence switch is standing in position 1, the relay 91, in attracting its armatures as a result of the closure of this circuit, opens 85 90 at its left-hand armature and back contact the energizing circuit for relay 92, which relay, as has already been explained, controls the selection of the position. If the operator's sequence switch 300 is standing in 95 position 17 when the listening-in key 191 is pressed, the energization of the relay 91 opens, at the right-hand armature and back contact of that relay, the path over which the relay 192 receives its energizing current 100 from conductor 140 when all of the operators' sequence switches 300 of this group of operators have been moved out of position 1 and are standing in position 17, or in some position between 2 and 18. Therefore, 105 if the operator presses her listening-in key 191 an instant before the last of the series of sequence switch contacts 308 (2 to 18) is closed, her sequence switch 300 will be prevented from being restored to position 1 110 110 where it would render the position immediately accessible to an incoming call which, when it seized a connecting cord, would automatically disconnect the operator's telephone from the cord circuit she was attempting to supervise.

In moving from the listening-out position 15 to the listening-in position 7 as a result of the pressing of the listening-in key 191, the listening key sequence switch when it reaches position 2 closes a circuit that extends from battery through the right-hand winding of the relay 91, conductor 137, and listening key sequence switch contact 415 120 (2 to 9) to ground. The relay 91 is thus 125 held energized to prevent the selection of the operator's position or to prevent the return of the operator's sequence switch to the waiting position 1 as long as the listening key sequence switch is in the listening-in 130

position. To hold the relay 91 energized during the interval that elapses between the momentary completion of its energizing circuit by the pressing of the listening-in key 191 and the continuing closure of its energizing circuit by way of the listening key sequence switch contact 415 (2 to 9), the relay 142, which has its winding in parallel with the left-hand winding of the relay 91, is arranged to close a locking circuit for itself and the relay 91, this locking circuit extending by way of the inner front contact and armature of relay 142, operator's sequence switch contact 305 (16 $\frac{1}{4}$ to 15), and the right-hand front contact and armature of relay 125 to ground, and remaining closed, under the control of the operator's sequence switch, for an interval greater than that normally required for the listening sequence switch to effect the continuing closure of the circuit of relay 91.

If the operator's sequence switch is standing in position 1 when the listening-in key 191 is pressed, the relay 142 in operating closes a circuit that extends from battery through the motor magnet and contact 308 (1) of the operator's sequence switch, outer front contact and armature of relay 142, operator's sequence switch contact 306 (1 to 9), and right-hand front contact and armature of relay 125 to ground. The closure of this circuit moves the operator's sequence switch out of position 1; and as the locking circuit of the relay 142 is interrupted at operator's sequence switch contact cam 305 as the switch passes beyond position 15, the sequence switch comes to rest in position 17. If the operator's sequence switch is standing in position 17 when the listening-in key 191 is pressed, the relay 142 in operating closes a circuit that extends from battery through the motor magnet and contact 308 (17) of the operator's sequence switch, outer front contact and armature of relay 142, operator's sequence switch contact 306 (10 to 18), right-hand back contact and armature of relay 95, and right-hand front contact and armature of relay 125 to ground. The closure of this circuit moves the operator's sequence switch out of position 17; and as the relay 142 is held locked up until the operator's sequence switch in its movement passes beyond position 15, the sequence switch continues its rotation until it returns to position 17 from which it started. The object of thus rotating the operator's sequence switch from position 17 to position 17 when the listening-in key 191 is pressed, is to maintain the relays 142 and 91 energized for a definite time interval in order to prevent the return of this particular operator's position to a selectable condition by the operation of relay 192 while the listening key sequence switch is moving from its listen-

ing-out position 15 to its listening-in position 7, and to release these relays positively at the expiration of that interval. If the relay 91 were not held continuously energized during this interval, or during that part of it which elapses before the energizing circuit of the right-hand winding of relay 91 is closed at contact 415 (2 to 9) of the listening key sequence switch, the closure of the cam series 308 by way of conductor 139 after the momentary depression of the listening-in key 191, would operate the relay 192 to return the operator's sequence switch to its waiting position 1, where the position could be selected by a call that would act, as already described, to interfere with the supervision of the existing connection.

In the foregoing, the organization that prevents a position being selected, or made selectable, after the operator has pressed one of her listening-in keys, has been described. The system is also so organized that all of the listening-in keys are made ineffective to bring about supervision from the moment the position is selected by an incoming call until the call has seized, or had an opportunity to seize, a connecting circuit. It will be remembered that the path to ground which the listening-in key closes for the movement of the listening key sequence switch out of position 15 includes the right-hand armature and back contact of the relay 195, and the right-hand back contact and armature of the relay 95. The result is that the energization of the relay 95, at the moment the operator's position is selected, instantly interrupts the path to ground by way of the right-hand back contact and armature of relay 95, and renders all of the listening-in keys 191 ineffective. At the same time the relay 195 is operated over the previously-described circuit closed at the left-hand front contact and armature of the relay 95, and the relay 195 is maintained operated by the locking circuit closed at the left-hand front contact and armature of relay 145 until that relay is released either by the operation of relay 153 when the connecting cord is seized by incoming call, or by the opening of its circuit at operator's sequence switch contact 302 (18 $\frac{1}{4}$ to 15) when the operator's sequence switch moves beyond position 15. If the path to ground for rendering the listening-in keys 191 effective were under the control of the right-hand back contact and armature of relay 95 alone, the listening-in keys would be restored to operativeness when the relay 95 fell back after its momentary energization. But being also under the control of the right-hand back contact and armature of relay 195, the path to ground for the use of the listening-in keys 191 is not reestablished until the connecting

cord has been seized by the incoming call, or until an interval sufficient for such seizure, as determined by the movement of the operator's sequence switch from position 1 through position 15, has elapsed.

As has been described, when the relay 142 is operated either by the pressing of a listening-in key 191 or by the operation of the relay 95 upon the selection of the position, it closes a locking path to ground by way of operator's sequence switch contact 305 (16 $\frac{1}{2}$ to 15) and the right-hand front contact and armature of relay 125. In order that this path to ground may not be effective to permit the listening-in keys 191 to control their sequence switches in the interval between the selection of the position and the selection of a connecting cord, the relay 195 is arranged to open at its left-hand armature and back contact the connection which normally exists by way of conductor 138 between the listening-in keys 191 and the energizing windings of the relays 142, 91 and 193.

As has hereinbefore been explained, as long as the connecting cord circuits of a position are idle or selectable, the high potential battery 251 is connected with the corresponding test terminal 118 of each cord circuit on the cord selector switch by way of the lower back contact and armature of the common relay 134, conductor 128, right-hand armature and back contact of relay 119, lower back contact and armature of relay 155, listening key sequence switch contact 404 (1), and conductor 88. Included in the common part of these connecting cord test circuits, is the energizing winding and the right-hand armature and back contact of a protective relay 197; and a protective non-inductive resistance, which may conveniently be wound upon the relay 197, is bridged across the right-hand armature and contact of the relay, and is normally short-circuited by them. If now an abnormal flow of current passes over the test circuit, such as might be occasioned by the engagement of a grounded brush with any of the test terminals 118 on the cord selector, or by the accidental grounding of any of the branches of the test circuit, the relay 197 operates, and, in opening the path by way of its right-hand back contact and armature, introduces into the circuit the non-inductive protective winding or resistance. The introduction of this resistance into the test circuit prevents the current flow in the circuit from attaining a value that might be injurious to the winding of the protective relay 197.

The relay 197 in operating also opens a circuit that is closed for energizing relay 125 when the operator's telephone plug is inserted in the telephone jack 126. This circuit extends from battery through the winding of the relay 125, local contacts 127 of

the telephone jack 126, and left-hand back contact and armature of relay 127 to ground. It may be explained at this point that as long as this circuit is closed and the relay 125 energized, a path to ground is closed by way of contacts 303 (4) and the left-hand front contact and armature of the relay 125, so that the operator's sequence switch is moved through or out of position 4, and comes to rest in positions 1 or 17. When the energizing circuit of the relay 125 is opened and the armatures of the relay retracted, a path to ground is closed by way of contact 303 (1 to 17) and the left-hand back contact and armature of relay 125 so that the operator's sequence switch is moved through positions 1 and 17 and can come to rest only in position 4. The result, therefore, of the operation of relay 197 upon the accidental grounding of the test circuit, is to interrupt the energizing circuit of the relay 125, thus causing the operator's sequence switch to move out of position 1 or 17 and come to rest in position 4, in which position the operator's position is inaccessible or unselectable.

When relay 125 is released as a result of this operation of relay 197, it opens at its right-hand front contact and armature the ground path for a number of the operator's position controlling circuits, including the circuit by means of which the listening-in keys 191 are made effective. As the accidental grounding of the test circuit may occur when there are a number of connections up on the operator's position, it is necessary that the operator may be able to continue to supervise such connections although her position is made inaccessible for incoming calls. Therefore, when the protective relay 197 operates it closes a circuit that extends from battery through the winding of the relay 196, and the left-hand front contact and armature of the relay 197 to ground; and the relay 196 in operating closes a path from the conductor 130 to ground by way of the right-hand contact and armature of the relay 196. This ground path serves to continue the effectiveness of the listening-in keys 191, and to enable the operator to supervise existing connections during the interval that her position is made inaccessible to incoming calls by the operation of the protective relay 197. The relay 196 in operating also closes at its left-hand front contact and armature a circuit that causes the illumination of an alarm lamp 176 to call the attention of the switchboard attendant to the abnormal condition that exists.

It may occasionally happen that the armatures of the relay 95 may accidentally be held attracted when they should be released. Inasmuch as the energizing circuit of the relay 142 is maintained closed as long as the

relay 95 is energized, in order to prevent the continued energization of the relay 142 from causing a continuous rotation of the operator's sequence switch under these conditions, the path to ground for moving the operator's sequence switch out of position 17 by way of the outer front contact of relay 142 and the operator's sequence switch contact 306 (19 to 18) has its continuity controlled at the right-hand back contact and armature of relay 95. Therefore if the relay 95 should accidentally be held energized, the circuit closed at the outer front contact and armature of the relay 142 is ineffective to move the operator's sequence switch beyond position 17; and in that position incoming calls are prevented from reaching the operator. In order that the operator under these circumstances may continue to supervise existing connections, although the normal path to ground from the listening in keys 191 is being held open by the continued energization of the relay 95 and the associated relay 195, an alternative path to ground is provided that extends from the conductor 130 by way of the right-hand armature and front contact of relay 195, operator's sequence contact 302 (17) and right-hand front contact and armature of the relay 125. The existence of this path renders it possible for the listening-in keys 191 under these circumstances to control their associated listening key sequence switches.

In the normal operation of the system, as has been described disconnection is automatically effected when the relay 175 is deenergized upon the withdrawal of the calling plug 170 from the spring-jack of the called subscriber's line. It may occasionally happen that in inserting the plug 170 into the spring-jack in putting up the connection, the operator will fumble so as momentarily to release the relay 175 after it has been attracted as the plug is started into the spring-jack. In its first attraction, the relay 175 completes the circuit by way of the motor magnet and contact 503 (1) of the calling cord sequence switch, contact 413 (7) of the listening key sequence switch and left-hand front contact and armature of the relay 175, so that the calling cord sequence switch is moved to position 2. Then if the armatures of the relay 175 are momentarily retracted, the circuit for the energization of the relay 157 is completed by way of calling cord sequence switch contacts 512 (2 to 17) and left-hand back contact and armature of relay 175 to ground, the relay 157 thereupon locking up and closing the circuit for moving the connecting cord sequence switch continuously until it passes through position 17, at which point the locking circuit of the relay 157 is opened. In the present organization special provision is made to prevent such

movement of the calling cord sequence switch through position 17, as a result of fumbling in inserting the plug into the called line spring-jack, from releasing the holding relay 152 and thus disestablishing the connection. This is accomplished as follows:— Assume that the relay 157 has become locked up as described, and that the calling cord sequence switch is moving continuously through its various positions; when the sequence switch reaches position 17 $\frac{1}{2}$, a circuit is closed that extends from battery through the windings of the relays 151 and 154 in parallel, calling cord sequence switch contact 506 (17 $\frac{1}{2}$ to 18 $\frac{1}{2}$) and (4 to 2 $\frac{1}{2}$), and left-hand front contact and armature of relay 175 to ground, the relay 175 having in the meanwhile attracted its armatures as a result of the full insertion of the plug 170 into the spring-jack following the momentary fumbling and consequent deenergization of the relay. Relay 154 in operating closes a locking circuit for itself and relay 151 by way of its left-hand front contact and armature, calling cord sequence switch contact 506 (4 to 2 $\frac{1}{2}$), and thence to ground over the path already traced. Relay 151 in operating closes a circuit that extends from battery through the winding of the holding relay 152 and to ground at the front contact and armature of relay 151. Therefore when the calling cord sequence switch passes beyond position 18 $\frac{1}{2}$ in its continued rotation, the opening of the locking circuit of relay 152 at the contact 508 (1 $\frac{1}{2}$ to 18 $\frac{1}{2}$) of the sequence switch does not cause the deenergization of the holding relay 152, which relay now has another energizing path by way of the outer front contact and armature of the relay 151, and therefore maintains its armatures attracted to hold the connection.

When the calling cord sequence switch in its rotation reaches position 1, a circuit is closed that extends from battery through the motor magnet and contact 503 (1) of the calling cord sequence switch, contact 416 (15) of the listening key sequence switch (the listening key sequence switch having been advanced from position 7 to position 15 when the calling plug 170 was initially inserted), calling cord sequence switch contacts 507 (17 to 8) and (1), and right-hand front contact and armature of relay 154 to ground. This causes the calling cord sequence switch to move through position 1. Normally, when the calling cord sequence switch returns to position 1 it moves the listening key sequence switch out of position 15 by way of the circuit that extends through contact 403 (15) of the listening key sequence switch, contact 515 (1) of the calling cord sequence switch, and the right-hand back contact and armature of relay 154 to ground. But under the present circum-

stances the relays 151 and 154 are being held energized by their locking circuit extending by way of contact 506 (4 to 2 $\frac{1}{2}$) of the calling cord sequence switch, and therefore the circuit for moving the listening key sequence switch out of position 15 is held open at the right-hand back contact and armature of relay 154. When the calling cord sequence switch reaches position 10 2, it is moved through that position by the circuit which extends by way of contact 504 (2) of the calling cord sequence switch, contact 418 (8 to 15) of the listening key sequence switch, and left-hand front contact 15 and armature of relay 175 to ground. As the calling cord sequence switch moves past position 2 $\frac{1}{2}$ in this second cycle of its rotation, the locking circuit of the relays 151 and 154 is broken at calling cord sequence switch contact 506 (4 to 2 $\frac{1}{2}$), and these relays thereupon release their armatures. The locking circuit for the relay 152 an instant before has been reestablished by way of the right-hand front contact and armature of that relay and calling cord sequence switch contact (1 $\frac{1}{2}$ to 18 $\frac{1}{2}$). Therefore the connection has been held, and the calling cord sequence switch has been moved into position to proceed with its 20 regular cycle of operations for completing connection with the called subscriber's line.

In the present organization a signal is provided that notifies the operator when a calling plug 170 of a connecting circuit to 35 which no call has been extended is mistakenly inserted in the spring-jack of a line. When no call has been extended to a connecting circuit, the calling cord sequence switch rests in position 1. If under these 40 circumstances the calling plug 170 is inserted in a spring-jack, a circuit is completed that extends from battery through resistance coil 188, lamp 189, left-hand armature and contact of relay 119, calling cord sequence switch contact 513 (1), and interrupter 198 to ground. Therefore as long 45 as the plug 170 remains in the spring-jack a flashing signal is given upon the lamp 189, which signal the operator is instructed to 50 regard as a peremptory disconnect signal, warning her immediately to withdraw the plug. It will be noted that when the operator employs the wrong plug in plugging up a connection, relay 119 opens the test conductor 88. If the test conductor 88 were not 55 opened under these conditions it might be seized by a cord selector since at this time the connecting cord circuit is unguarded. The seizure of this cord selector would result in the interference of high potential test battery 251 with the set of class of service impulses common to the exchange.

In order to disclose fully the features to 60 which this invention is directed, it has been 65 desirable to describe them in connection

with other features that are the subject of co-pending applications assigned to the same assignee, such applications including the applications of S. B. Williams, Jr., Serial No. 75,328 filed January 31, 1916; Serial No. 75,329 filed January 31, 1916; Serial No. 107,090 filed July 1, 1916; Serial No. 180,633 filed July 14, 1917, (Case 33); the application of F. A. Stearn, Serial No. 107,540 filed July 5, 1916; and the application of R. L. Quass, Serial No. 107,012 filed July 1, 1916. Such other features are the subject of claims in the applications mentioned above, and are not claimed in the present application.

What is claimed is:—

1. The combination with an operator's position, of means for selecting the same and extending calls thereto, a plurality of connecting circuits associated with said position for receiving said calls, a test conductor associated with each of said connecting circuits for controlling the establishing of connection therewith, a relay common to said test conductors and responsive to abnormal current flow therein, and means controlled in the response of said relay for rendering said position unselectable by said call-extending means.

2. The combination with an operator's position, of means for extending calls thereto, a plurality of connecting circuits associated with said position for receiving said calls, testing means associated with said connecting circuits for controlling the establishing of connection therewith, and means responsive to an abnormal electrical condition of said testing means for rendering the connecting circuits of said position inaccessible to said call-extending means.

3. The combination with an operator's position, of a plurality of connecting circuits associated therewith; means for extending calls to the connecting circuits of said position, a test conductor for each of said connecting circuits, means for varying the electrical condition of each test conductor, an electro-magnet associated with said call-extending means for co-operating with said test conductors to control the extension of a call to any of the associated connecting circuits, a magnet common to said test conductors and responsive to abnormal current flow in any of them, operator's selecting apparatus associated with said call-extending means and governing the selection thereby of said operator's position, a test circuit for said operator's position controlling the operation of said operator's selecting apparatus, and means controlled by the operation of said common electromagnet for changing said test circuit to prevent the selection of said operator's position by said call-extending means.

4. The combination with an operator's position, of a plurality of connecting cir-

cuits therefor, a switch for extending calls to said position, means for causing said switch to select said position and then one of the connecting circuits thereof, operator's 5 telephone apparatus, a listening switch for each connecting circuit for controlling the connection of said telephone apparatus with the associated circuit, a test conductor associated with each connecting circuit for controlling the selection of the same by said call-extending switch, and means responsive to an abnormal flow of current in any of said test conductors for rendering said operator's position unselectable and maintaining 10 the operativeness of said listening switches.

5. The combination with an operator's position, of a plurality of connecting circuits therefor, a switch for extending calls to said 20 position, means for causing said switch to select said position and then one of the connecting circuits thereof, operator's telephone apparatus, a listening switch associated with each connecting circuit for controlling the connection of said telephone apparatus with the corresponding circuit, a test conductor for each connecting circuit for controlling the selection of the same by said call-extending switch, an alarm signal, and means responsive to an abnormal flow of current in any of said conductors for rendering said operator's position unselectable, maintaining 25 the operativeness of said listening switches, and actuating said alarm signal.

35. 6. The combination with an operator's position, of means for extending calls thereto, a plurality of connecting circuits associated with said position for receiving said calls, testing means associated with said connecting 40 circuits for controlling the establishing of connection therewith, an alarm signal, and means responsive to an abnormal electrical condition of said testing means for actuating said alarm signal and rendering the connecting 45 circuits of said position inaccessible to said call-extending means.

7. The combination with an operator's position, of a plurality of connecting circuits therefor, call-extending means for selecting 50 said position and then one of the connecting circuits thereof, a signal and a timing switch at said position, means made operative upon the selection of said position for independently actuating said signal and said timing 55 switch, means controlled by said timing switch for causing the withdrawal of said signal after a predetermined time interval, and means actuated upon the selection of a connecting circuit for withdrawing said signal independently of its control by said timing switch.

60. 8. The combination with an operator's position, of a plurality of connecting circuits therefor, a switch for extending calls to said

position, means for causing said switch to 65 select said position and then one of the connecting circuits thereof, a signal and a timing switch at said position, a relay momentarily actuated by the selection of said position, means controlled in the momentary actuation of said relay for causing the independent and continuing energization of said signal and said timing switch, means controlled by said timing switch for causing the deenergization of said signal after a predetermined time interval, and means actuated upon the selection of a connecting circuit by said call-extending switch for withdrawing said signal independently of its control by said timing switch. 75 80

9. The combination with an operator's position, of a plurality of connecting circuits therefor, call-extending means for selecting said position and then one of the connecting circuits thereof, means actuated in the selection of said position for rendering the same unselectable, means for restoring the selectability of said position, a listening switch for each of said connecting circuits, and a timing switch operated by the operation of any of said listening switches when said operator's position is unselectable for rendering said restoring means inoperable for a predetermined interval and then restoring its operability. 95

10. The combination with an operator's position, of a plurality of connecting circuits therefor, call-extending means for selecting said position and then one of the connecting circuits thereof, means actuated in the selection of said position for rendering the same unselectable, means for restoring the selectability of said position, a listening key for each of said connecting circuits, timing mechanism operable by any of said listening keys in the unselectable condition of said position, and means for preventing the operation of said restoring means, said preventing means acting under the control of said timing mechanism to render said restoring means inoperable for a predetermined interval after said listening switch is operated and then restore its operability. 100 105 110

11. The combination with an operator's position, of a plurality of connecting circuits therefor, call-extending means for selecting said position and then one of the connecting circuits thereof, a listening key for each of said connecting circuits, means actuated in the selection of said position or in the operation of any of said listening keys for rendering said position unselectable, means for restoring the selectability of said position, and timing mechanism operable by the actuation of any of said listening keys while said operator's position is in its unselectable condition, said timing mechanism acting to render said 115 120

restoring means inoperable for a predetermined interval after said listening key is actuated and then restore its operability.

12. The combination with an operator's 5 position, of a plurality of connecting circuits therefor, call-extending means acting to select said position and then one of the connecting circuits thereof, means actuated in the selection of said position for rendering the same unselectable, means for restoring the selectability of said position, a listening key for each of said connecting circuits, a timing mechanism operated by the operation of any of said listening keys when said 10 operator's position is in its unselectable condition for rendering said restoring means inoperable for a predetermined interval and then restoring its operability, and a listening sequence switch associated with each of 15 said connecting circuits and operated by the actuation of the associated listening key, said listening sequence switch normally acting to render said restoring means inoperable before the expiration of the time interval determined by the operation of said timing mechanism.

13. The combination with a connecting circuit, of means for extending a call thereto, a called line, means for extending said 30 connecting circuit to said called line, means for producing a flashing disconnect signal made operative in extending said connecting circuit to said called line, and means made operative in the extension of a call to said 35 connecting circuit for rendering said flashing disconnect signal inoperative.

14. In a call distributing system, the combination with a plurality of telephone lines, of a connecting circuit, automatic switching 40 means for extending a calling line to said connecting circuit, a manual switch for extending said connecting circuit to a called line, means for producing a flashing disconnect signal made operative in closing said 45 manual switch in extending said connecting circuit to said called line, and means made operative in the actuation of said automatic switching means in extending a calling line to said connecting circuit for rendering said 50 flashing disconnect signal inoperative.

15. The combination with two telephone lines and a connecting circuit uniting the same, of means responsive to a momentary interruption of the connection between said 55 connecting circuit and one of said lines for causing the disconnection of said connecting circuit from the other line after a predetermined interval, and means responsive to a renewed closure of the connection between 60 the connecting circuit and the first-mentioned line within said predetermined interval for preventing the disconnection of said connecting circuit from said other line.

16. The combination with two telephone

lines and a connecting circuit uniting the 65 same, of a holding magnet for maintaining the connection of the connecting circuit with one of said lines, means responsive to a momentary interruption of the connection between said connecting circuit and the other line for causing the deenergization of said holding magnet after a predetermined interval, and means responsive to a renewed closure of the connection between the connecting circuit and the last-mentioned line 70 within said predetermined interval for preventing the interruption of the energizing circuit of said holding magnet.

17. The combination with a calling line and a called line, of a connecting circuit having an automatic switch connecting it with said calling line and a manual switch for connecting it with said called line, means actuated by a momentary closing and opening of said manual switch for operating said 80 automatic switch to disconnect said connecting circuit from said calling line after the expiration of a certain time interval, and means responsive to a renewed closure of said manual switch prior to the expiration 85 of such time interval for preventing the operation of said disconnecting means.

18. The combination with two telephone lines and a connecting circuit uniting the same, of a manual switch controlling the 90 connection of said connecting circuit with one of said lines, a sequence switch, means actuated by the closing of said manual switch for moving said sequence switch from its normal to its talking position and actuated by the opening of said manual switch for returning said sequence switch from its talking to its normal position, means controlled by said sequence switch in returning from its talking to its normal position for disconnecting said circuit from the other of 95 said lines, electromagnetic mechanism for preventing the operation of said disconnecting means and for causing the sequence switch to pass through its normal position and into its talking position again, and an energizing circuit for said electromagnetic mechanism completed by a closed condition 100 of said manual switch as said sequence switch moves out of its talking position.

19. The combination with two telephone lines and a connecting circuit uniting the same, of an automatic switch controlling the connection of said circuit with one of said lines, a plug and spring-jack controlling the 120 connection of said circuit with the other of said lines, a sequence switch associated with said connecting circuit, means actuated by the insertion of the plug into the spring-jack for moving said sequence switch from 125 its normal to its talking position and actuated by breaking the connection between said plug and spring-jack for returning said se-

- quence switch from its talking to its normal position, a holding magnet controlling said automatic switch to hold its associated line in connection with said connecting circuit, an 5 energizing circuit for said holding magnet broken as said sequence switch moves out of its talking position, and means for preventing the breaking of said holding magnet circuit and for causing said sequence switch to 10 pass through its normal position when it returns thereto, said means being made operative by the presence of the plug in the spring jack as said sequence switch moves out of its talking position.
- 15 20. The combination with an operator's position, of a plurality of connecting circuits therefor, a switch for extending calls to said position, means for causing said switch to select said position and then one of the connecting circuits thereof, operator's telephone apparatus, a listening switch for each connecting circuit for controlling the connection of said telephone apparatus with the associated circuit, a switch temporarily actuated 25 upon the selection of said position for rendering said position unselectable and said listening switches ineffective, and means made operative by an unduly protracted closure of said switch for again making said listening switches effective.
- 30 35 40 21. The combination with an operator's position, of a connecting circuit therefor, operator's telephone apparatus, a listening switch for connecting the same with said connecting circuit, means for causing the selection of the operator's position by an incoming call, an electro-magnet actuated by said selection for rendering said listening switch inoperative, and means made operative by an abnormally protracted actuation

of said electro-magnet for restoring the operativeness of said listening switch.

22. The combination with an operator's position, of a plurality of connecting circuits therefor, a call-extending means for selecting said position and then one of the connecting circuits thereof, a test circuit at said operator's position controlling the selection thereof, a sequence switch and a relay controlling said test circuit, either said relay or said sequence switch acting when operated to change said test circuit to render said position unselectable, and means actuated upon the selection of said position for actuating said relay and said sequence switch independently of each other.

23. The combination with an operator's position, means for selecting the same, a sequence switch, means controlled thereby for rendering said position unselectable, and a relay actuated in the selection of said position for actuating said sequence switch and independently actuating the aforesaid means for rendering said position unselectable.

24. In a telephone exchange system, two groups of lines, selecting means for connecting a line of one group with a line of the other group, a test conductor associated with each of said lines of said other group for controlling the establishment of connection therewith, a relay common to said test conductors and responsive to abnormal current flow therein, and means controlled in the response of said relay for rendering said other group of lines unselectable by said selecting means.

In witness whereof, I hereunto subscribe my name this 1st day of October A. D., 1917.

RALPH L. QUASS.
